[57] CLAIM

The ornamental design for a freeze plug tool, as shown and described.

DESCRIPTION

FIG. 1 is a perspective view of my freeze plug tool showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a bottom plan view thereof; and

FIG. 7 is a perspective view of an alternate embodiment of my freeze plug tool similar to FIG. 1, but showing a lower portion which is symmetrical in configuration to illustrate the totality of the design thereof.

Fig. 1.

Fig. 2.

Fig. 3.

Fig. 4.

Fig. 5.

Fig. 7.
